UNITED STATES PATENT OFFICE.

FRANK MOSSBERG, OF ATTLEBORO, MASSACHUSETTS, ASSIGNOR TO MOSSBERG PRESSED STEEL CORPORATION, OF ATTLEBORO, MASSACHUSETTS, A CORPORATION OF MASSACHUSETTS.

CARRIER FOR BRAIDING MACHINES.

Application filed August 24, 1923. Serial No. 659,105.

To all whom it may concern:

Be it known that I, FRANK MOSSBERG, a citizen of the United States, residing at Attleboro, in the county of Bristol and State of Massachusetts, have invented certain new and useful Improvements in Carriers for Braiding Machines, of which the following is a specification.

This invention relates to improvements in the construction of braiding machine carriers; and has for its object to provide a carrier which is extremely light in weight, whereby high-running speed may be obtained; and the carrier is provided with a coiled spring acting upon the tension weight to accelerate its take-up action upon the yarn while the carrier is running at this high rate of speed.

A further object of the invention is to form many of the operating parts of the carrier of pressed sheet metal thereby greatly reducing the weight of the carrier.

A still further object of the invention is to provide a pair of cooperating standards on the carrier, one serving as a vertical guide for the weight and the spring for operating the weight and the other serving to cooperate with the first standard to provide a lateral guide for the weight, the second standard serving primarily as a vertical guide for the lift member, which lift is also guided against lateral movement on the weight standard.

This invention further consists in the utilizing of both of these standards as thread guides to cooperate with the guide on the bottom weight whereby the thread may be readily passed into all of these open ended guides without being obliged to pass the end of the thread through any of them.

With these and other objects in view, the invention consists of certain novel features of construction, as will be more fully described, and particularly pointed out in the appended claims.

In the accompanying drawings:—

Figure 1 is a side elevation showing my improved construction of carrier with the tension weight in lifted position.

Figure 2 is a top view sectioned on line 2—2 of Figure 1.

Figure 3 is a perspective view of the latch lifting member.

Figure 4 is a perspective view of the tension weight. 55

Figure 5 is a perspective view of the latch member removed.

Figure 6 is a side elevation partly in section illustrating the top guide for the tension weight, and showing the manner of connecting the thread-guide to the weight. 60

It is found in practice of importance in order to obtain a high speed braiding machine, to form the carrier as light as possible and to also provide means whereby the tension will act quickly to take up the slack in the yarn, also to set the weight standard and the lift standard on the longitudinal center line through the base so as to obviate the necessity of making right and left 70 handed carriers; and the following is a detailed description of one construction of carrier by which these important results may be obtained.

With reference to the drawings, 10 designates the base of a carrier for the usual guide 11 adapted to run in the usual raceway of a braiding machine, said carrier being provided with a hub member 12 in which is mounted a package spindle 13. This hub is 80 pierced at 14 and the rock shaft 15 of the latch 16 is passed through this opening and a spring 17 is mounted to act upon this shaft so as to normally press the end of the latch into engagement with the teeth 18 of the package spool 19. The opposite end of this latch is provided with a laterally extending member 20 to project beneath the package and be engaged by the latch lift 21. This lateral projection also serves to engage, lift 90 and free the package if it should become stuck to its spindle or seat, and to also serve as a brake to prevent the yarn from overrunning.

On the top of this carrier, I have mounted 95 two standard members 22 and 23, both of which are set on the major axis through the base, thereby obviating the necessity of making right and left handed carriers. Each of these standards is preferably of small 100 diameter with its lower end forced into the hub 24 of the base. One of these standards being of a height considerably less than that of the height of the spindle 13, its end being reduced and bent to form an open thread 105 guide 26.

A tension weight or member 27 is mounted to slide vertically on this weight standard 22, the weight being preferably struck up from sheet stock having a horizontal plate 28 with its sides 29 turned downwardly to form stop-engaging arms, the plate being provided with forwardly projecting fingers 30 arranged to embrace the opposite standard 23 to prevent lateral rotation of the weight on its standard.

In order to provide an elongated bearing for this weight on its standard, I have formed a sleeve 31 having a reduced lower end 32 which is forced into the plate 28, the upper end of this tube being also reduced at 33 to receive the lower, closely wound coils of the tension spring 34.

The thread guide 35 on this weight is preferably formed from sheet stock having a hole formed in its body portion 36 through which the reduced end of the tube 31 passes, its shank portion 37 extending upwardly along this tube with its end bent over into hook shape to form an open-mouthed thread guide.

Tension is applied to this weight by means of a light coiled compression spring 34, the upper end of which is passed through a hole 38 in the standard 22, while the lower coils are arranged to engage the neck 33 and give the weight the desired amount of tension.

In order that the upward stroke of this weight member when it reaches the desired height, may lift the latch and release the spool or package to rotate and let off more yarn, I have formed a latch lifting member 21, preferably constructed of sheet metal, having a finger 39 extending into engagement with the member 20 of the latch, its rear end being notched as at 40 to engage and slide on the standard 22 thereby preventing lateral movement of this engaging finger. This finger is provided with a hole 41 forming a lower bearing for the reception of the guide standard 23 and a widely spread upper bearing 42 is provided also having an opening for the reception of the standard 23, and these lower and upper bearings are connected by means of the connector member 43 whereby this lift member is guided vertically on its standard. This upper bearing 42 is engaged by the fingers 30 on the weight to raise the latch lifting member to rock the latch on its shaft to release the package spool when more yarn is required.

If for any reason the package should stick on its base or spindle and refuse to rotate, the tension weight will continue to rise and through the lifter raise the rear of the latch into engagement with the bottom of the spool to also lift and free it, thus preventing breakage of the yarn.

By my improved construction of carrier 65 the cooperating parts are extremely light in

weight and are merely guided to perform their function with the minimum amount of frictional resistance, thereby permitting the carrier to run at an extremely high rate of speed and still operate to produce the desired results.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A carrier for braiding machines having a package spindle, a tension weight guide standard, a weight slidable thereon, a coil compression spring on said standard acting upon said weight, a feed control latch, and a guide standard for the latch lift located intermediate said weight standard and package spindle.

2. A carrier for braiding machines having a package spindle, a tension weight guide having a thread guide at its upper end, a weight slidable on said standard, a compression spring on said standard acting on said weight, a spring pressed package feed control latch, a lift for said latch operated by a movement of said weight, a separate guide standard for said lift and having a thread guide whereby tension of the lift lifts the weight to lift the latch through the latch lift against the tension of said spring.

3. A carrier for braiding machines having a package spindle, a tension-weight guide standard and a latch lift guide standard all located in substantially the same radial alignment, a spring pressed weight slidable on its standard and guided on said lift standard, a lift having widely separated upper and lower guides slidable on its standard and also having a lateral guide slidable on said weight standard, a spring pressed package feed control latch and a finger on said lift extending into engagement with said latch whereby the tension of the thread lifts the weight and the latch through its lift member.

4. A carrier for braiding machines having a package spindle, a tension weight guide standard and a latch lift guide standard all located in substantially the same radial alignment, a spring pressed weight slidable on its standard having a thread guide and a thread guide in each of said standards whereby the thread is led from the package through the guide in the lift standard, the guide in the weight and out through that in the weight standard.

5. A carrier for braiding machines having a package spindle, a tension-weight guide standard of a height at least that of the package spindle and having a thread guide eye formed in its end, a weight pressing

spring mounted on said standard, a latch lift guide standard of a height less than that of said spindle and having a thread guide eye formed in its end, said guide standard being located intermediate the weight standard and the package spindle.

6. A carrier for braiding machines having a package spindle, a weight guiding standard, a compression spring on said standard

acting upon said weight, a pivoted package feed controlling latch having a portion extending beneath the package but normally clear of the same, and a connector between the weight and latch whereby an excessive upward movement of the weight moves the latch to raise the package from its seat.

In testimony whereof I affix my signature.

FRANK MOSSBERG.
